Primary Examiner — Andrew T Nemeth

(57) **CLAIM**

The ornamental design for a ball throwing device for a pet, as shown and described.

DESCRIPTION

2.1: Perspective

2.2: Front

2.3: Back

2.4: Left

2.5: Right

2.6: Top

2.7: Bottom

FIG. **2.1** is a back, left, bottom perspective view of a ball throwing device for a pet showing my new design; FIG. **2.2** is a front perspective view thereof; FIG. **2.3** is a back perspective view thereof; FIG. **2.4** is a left side perspective view thereof; FIG. **2.5** is a right side perspective view thereof; FIG. **2.6** is a top perspective view thereof; and FIG. **2.7** is a bottom perspective view thereof.

1 Claim, 7 Drawing Sheets
